UNITED STATES PATENT OFFICE.

JAMES M. MAHER, OF FREEMONT, NEBRASKA.

PORTABLE TRACK DEVICE FOR MOTOR-VEHICLES.

1,222,781.

Specification of Letters Patent. Patented Apr. 17, 1917.

Application filed August 14, 1916. Serial No. 114,746.

To all whom it may concern:

Be it known that I, JAMES M. MAHER, a citizen of the United States, residing at Fremont, in the county of Dodge and State 5 of Nebraska, have invented certain new and useful Improvements in Portable Track Devices for Motor-Vehicles, of which the following is a specification.

My invention relates to devices for extricating motor vehicles when the same are mired in mud, loose sand or the like.

It is the object of my invention to provide a simple, inexpensive and efficient device for the above purpose, having means which may 15 be placed in engagement with the driving wheels of the vehicle so that rotation of the wheels will propel the vehicle and enable the same to move out of the mire under its own power.

20 A further object of my invention is to provide a device of the character described capable of being folded so as to occupy only a moderate space when not in use.

With the above and other objects in view 25 which will appear as the description proceeds, the invention consists in the novel construction, combination and arrangement of parts, hereinafter described and claimed, it being understood that changes in the precise embodiment of the invention herein disclosed can be made without departing from the spirit of the invention.

In the accompanying drawings, I have 35 illustrated one complete example of the physical embodiment of my invention constructed according to the best mode I have so far devised for the practical application of the principles of my invention.

Figure 1 represents a side elevation of a 40 vehicle wheel with my track applied thereto. The track being shown in the position it occupies before receiving the strain from the wheel.

Fig. 2 represents a top plan view of the 45 two ends of my track device.

Fig. 3 represents a perspective view of a portion of one of the slats used in my track, showing the manner of connecting the slats to the links, and

50 Fig. 4 represents a similar view of a modified form of link.

Referring by numeral to the drawing, in which similar characters of reference denote like parts in all the views:

55 The numeral 1, designates the chain proper consisting of the malleable iron links

2, and the shorter malleable links 3, secured to the first-named links by means of the usual malleable iron loose joint connections 4.

Two of these chains are utilized to form one track and are connected together by means of the slats 5, riveted at 6 to the links 3. The slats 5 are preferably of hard wood, but may be of any material which will withstand the hard usage to which it would be given.

Secured to one end of the track is the chain 7 having the center ring 8 through which the iron pin 9 is driven in the ground 70 to hold the track stationary and allow the wheel to strain thereon. The track has secured to its other end the chain 10 which is used in placing the track under the wheel. This is accomplished by placing the chain 75 10 as far under the wheel 11 as possible and the rotating of the wheel tends to draw the track proper under the wheel until it becomes taut, when the wheel will pull itself out of the mire, the track preventing the 80 wheel from spinning around as is the case when a track is not used.

In the form of link shown in Fig. 4, the link 3' is provided with the angular opening 32 which fits over the end of the slat 5, and 85 has the opening 4' for connecting with the links 2 by any desired pin or other connection.

It will be obvious that in the use of the apparatus for a vehicle of which both driving wheels are mired, one of the track devices will be required for each driving wheel, but it is seldom, if ever, necessary to use more than two of the track devices to extricate the vehicle where the same is not so 90 deeply mired as to entirely prevent its operation. It may be noted that for different vehicles different sizes of the track may be required, since those suitable for large and heavy vehicles would be unnecessarily heavy 95 and bulky for lighter vehicles. In general it is advisable that the length of track be equal to or slightly greater than the diameter of the wheels of the vehicle, and that the width of the track be equal to about one-half the 100 diameter of the tire.

I claim:—

1. A portable track device for motor vehicles comprising a flexible strap made up of parallel linked chains and cross bars fixed 110 to certain of the links forming said parallel chains, a chain having its ends secured to

one end of the strap and adapted to be fixed to the ground, and an initial traction chain at the other end of said strap.

2. A portable track device for motor vehicles, comprising a flexible strap made up of side chains and cross bars fixed to said chains, an attaching chain at one end of the strap, and an initial traction chain at the

other end thereof, said chain being composed of a series of long and short links. 10

In testimony whereof I affix my signature in the presence of two witnesses.

JAMES M. MAHER.
